UNITED STATES PATENT OFFICE.

HENRI L'HUILLIER, OF PARIS, FRANCE.

APPARATUS FOR DYEING.

No. 820,654.

Specification of Letters Patent.

Patented May 15, 1906.

Application filed July 6, 1905. Serial No. 268,455.

To all whom it may concern:

Be it known that I, HENRI L'HUILLIER, chemical engineer, a citizen of the Republic of France, residing at Paris, in the Republic of France, have invented certain new and useful Improvements in Apparatus for Dyeing Threads on Cops and Pirns, (for which application has been made in France January 24, 1905, No. 350,981; Austria-Hungary, April 7, 1905; Germany, February 9, 1905, and Belgium, January 25, 1905,) of which the following is a specification.

This invention has for its object an improved apparatus for dyeing threads of yarn on cops or pirns.

In this arrangement the cops to be dyed are mounted on hollow perforated spindles permanently fixed on the pipes conveying the dye-bath. These pipes are connected in sets of four by means of a union which connects with a central conduit running from one end of the vat to the other. This central conduit is movable and is detachably connected, by means of lower tubes, to another conduit fixed on the bottom of the vat. The spindle-carrying pipes thus form a sort of rack in one with the central feed-conduit and may be removed as a single piece. In this manner the handling is extremely simple, resulting in a saving of labor and efficient working of the vat. Further, by this invention the cops when placed on the spindles cannot be displaced or lifted by the pressure of the liquid, because they are held by means of strips, which prevent their lifting.

The method of carrying out the invention is hereinafter described with reference to the accompanying drawings, in which—

Figure 1 is a plan view, and Fig. 2 a trans-
section, of the vat; Fig. 3, an elevation, on an enlarged scale, of the end of a pair of tubes; and Fig. 4, a plan view of this end.

The apparatus comprises a rectangular vat 1, preferably of wood. The cops 2 to be dyed are fitted on perforated hollow spindles 3, fixed by soldering or otherwise on rows of pipes 4. These pipes are arranged in pairs on the right and left sides of the vat and are connected in sets by means of a union piece 5, provided beneath with a neck 6, which fits into a corresponding socket 7 on a central conduit 8. The various branches are thus arranged parallel to each other, so as to occupy the whole of the vat. The conduit 8 is provided with several pipes 9, which fit into necks 10, connecting with a pipe 11, arranged

beneath the vat. An india-rubber washer 12 insures the tightness of the joint. The dye-bath or the like being supplied by the pipes 4 and rising through the hollow spindles 3 to traverse the cops or pirns tends to lift them and deform them. The consequence is that the dye-bath does not traverse them uniformly and irregularities are produced. In order to remedy this draw- 6c back, the following arrangement has been de- 65 signed: The adjacent ends of the pipes which form a pair are connected by cross-pieces 13, which serve as supports to vertical rods 14. In connection with these are arranged flat 70 strips 15, connected by plates 16, and in the middle of the latter sockets 17 are fixed. When the cops are in place, the pairs of strips 15 are placed along each double row of cops, so as to bear on the conical heads of the cops 75 and keep them on the spindles. The engage- 80 ment of the sockets 17 with the rods 14 keeps the strips 15 in place, and the weight of these latter suffices to hold the cops. If this be not sufficient, the rods 14 may be arranged to project above the plates 16 and provided with fixing devices. As the strips 15, as shown, are quite thin, and therefore flexible, they retain the cops in place without unduly compressing some of them, while leaving 85 others free, as would result with a rigid piece. Also it is to be noted that the strip 15 only moves contact with each cop at a single point, thereby preventing spots which would result from a more extended contact. In order to 90 enable the conduit 8 to be taken out and re- placed, the walls of the vat are provided with grooves 18, in which tongues at each end of the conduit 8 engage.

The cover (not shown in the drawings) is 95 provided with the necessary pipes for estab- lishing communication with a circulation- pump and a vacuum-pump, also a manô- meter, a tap for the readmission of air, and other connections, as desired. The bottom 100 of the vat is provided with steam-coils 19 for heating the bath.

The working of the apparatus is as follows: When the spindles have been fitted with cops or pirns and the whole is placed in the vat 105 and the lid fixed, the vacuum-pump is set in operation. The dye-bath is then drawn into the vat by the pipe 11, the conduit 8, the pipes 4, and the perforated spindles 3 through the cops or pirns. By opening the air-tap 110 pressure is reestablished in the upper part of the vat, and the dye-bath redescends by

gravitation. The operation may be repeated several times if such be deemed necessary. Washing may be done in the same manner. The liquid may also be caused to circulate in 5 the vat by means of a pump. When the operation is terminated, the conduit 8 and all the pipes, carrying the spindles with their bobbins, is removed in a single piece, and the vat is provided with a fresh set of pipes carrying spindles, which has been prepared outside the vat. From this it is evident that the operations in the vat may succeed one another without interruption other than that necessary for removing one set of spindle- 15 carrying pipes and replacing it by another, which operation is facilitated by the circumstance that all the pipes are mounted on the central conduit, so that they may be simultaneously removed. The cops may be dried 20 on the spindles by sending a current of warm air under pressure through the central conduit 8 and forcing it through the cops.

I declare that what I claim is—

1. In an apparatus for dyeing threads on spindles in order to have a circulation of liquid, the combination of rectilinear pipes, perforated spindles fitted thereon, cops mounted on said spindles with blades making contact with the head of the cops for preventing the 25 cops being lifted on the spindles, substantially as described.
2. In an apparatus for dyeing threads and yarns in cops, the combination of a conduit, spindle-carrying pipes arranged at an angle 30 to said conduit and parallel to each other, and strips adapted to prevent the cops of the same row from being lifted, substantially as described.
3. In an apparatus for dyeing threads in 35 cops, the combination of spindle-carrying pipes connected in pairs, cross-pieces connecting the ends of the pipes of each pair, rods mounted on said cross-pieces, strips for

4. preventing the cops from being lifted on the spindles, plates connecting the ends of the 45 strips, and hollow rods fixed at one end on said plates and at their other ends telescoping onto the first-named rods.

5. In an apparatus for dyeing threads and yarns in cops, the combination of a vat, a removable rectilinear conduit therein, rectilinear pipes fixed to and connecting with said conduit in pairs and arranged transversely thereto and parallel to each other, hollow perforated spindles carried by said pipes, 55 cross-pieces connecting the ends of the pipes of each pair, guide-pieces projecting from said cross-pieces, thin flexible strips in contact at a single point with the heads of the rows of cops for retaining the cops upon the 60 spindles, other cross-pieces connecting together the ends of the strips, and other guide-pieces projecting from the last-named cross-pieces and telescoping with the first-named 65 guide-pieces.

6. In an apparatus for dyeing threads and yarns in cops, the combination of spindles arranged in rectilinear rows, and a thin flexible blade contacting at a single point with the 70 head of each cop in a row for retaining the cops upon the spindles.

7. In an apparatus for dyeing threads and yarns in cops, the combination of hollow perforated upwardly - projecting spindles arranged in rectilinear rows, a thin flexible 75 blade resting with its weight upon the heads of the cops in a row and making contact with each cop at a single point, and means for guiding said blades.

In witness whereof I have hereunto signed 80 my name, this 31st day of May, 1905, in the presence of two subscribing witnesses.

HENRI L'HUILLIER.
